THREE-WHEEL MOTORCYCLE

Walter E. Brown, North Wilbraham, Mass., assignor to The Indian Company, a corporation of Delaware

Application July 12, 1952, Serial No. 20,598

Term of patent 14 years

(Cl. D90—8)

To all whom it may concern:

Be it known that I, Walter E. Brown, a citizen of the United States residing at North Wilbraham, Commonwealth of Massachusetts, have invented a new, original, and ornamental Design for a Three-Wheel Motorcycle, of which the following is a specification, reference being had to the accompanying drawing, forming a part hereof.

In the drawing:

Fig. 1 is a side perspective view of a three-wheel motorcycle embodying my new design;

Fig. 2 is a perspective from the rear; and

Fig. 3 is a front elevational view thereof.

The essential features of my design reside in those portions indicated by solid lines.

I claim:

The ornamental design for a three-wheel motorcycle, as shown and described.
